UNITED STATES PATENT OFFICE.

WILLIAM T. DONNELLY, OF BROOKLYN, NEW YORK.

WOODEN SHIP.

1,401,889.

Specification of Letters Patent. Patented Dec. 27, 1921.

Application filed December 6, 1917. Serial No. 205,799.

To all whom it may concern:

Be it known that I, WILLIAM T. DONNELLY, a citizen of the United States, and a resident of Brooklyn, in the county of Kings and State of New York, have invented certain new and useful Improvements in Wooden Ships, of which the following is a specification.

The invention relates to the construction of hulls of vessels, more particularly to hulls constructed of wood. It has for its object to increase the rigidity and stability of the structure, to render impossible the working of the bilge through yielding of bow and stem, and thus give the wooden ship the same general hull rigidity as the steel ship by providing an inner skin and double bottom.

In carrying out the invention, a continuous longitudinal bulkhead is provided from stem to stern posts, and is made an integral part of same; and, in addition, the side, bilge and bottom frames, as well as the top frame of the double bottom, are so assembled as to be placed under an initial stress sufficient to insure the desired rigidity.

The nature of the invention will be best understood when described in connection with the accompanying drawings, in which—

Figure 1 is a deck plan.

Fig. 2 is a side view of the ship with a portion broken away to disclose the interior.

Fig. 3 is a horizontal section through the ship.

Fig. 4 is a midship section of the ship.

Fig. 5 is a fragmentary detail side view.

Fig. 6 is a detail sectional view illustrating the laminated bilge construction.

Figs. 7 and 8 are fragmentary horizontal sections taken respectively on the lines 7—7 and 8—8, Fig. 6.

Similar characters of reference designate corresponding parts throughout the several views.

Referring to the drawings, wherein the invention is shown in its essential features, it being understood that various details of construction may be modified without departing from the spirit of the invention, 10 designates the keel, 11 the outer skin, and 12 the inner skin of the vessel. 13 designates the various decks, 14 the upper member of the double bottom, and 15 the lower member thereof. The double bottom 14—15 is formed, as hereinafter more particularly set forth, to maintain the upper member 14 thereof under a bending stress, the bilges 16

from same being curved and having the same radius throughout the length of the ship. In addition, a longitudinal bulkhead 17, centrally disposed in the hull, extends 60 the entire length of the said hull, is continuous throughout, and is so connected with the stem and stern posts 18 and 19 respectively as to be integral therewith to form a continuous member or beam of the hull. The 65 side frames 20 are united to the bilges 16 in manner hereinafter set forth, and are given a bending stress through a connection with the deck frames 13 in any well-known or special manner as by being bent inwardly 70 about the intermediate deck frame 13 as a pivot, and are thus under an initial stress with reference to an opening-up or yielding of the hull structure.

In view of the provision of the continuous 75 longitudinal bulkhead 17, hatches 21 are provided on opposite sides thereof; and it is to be understood, of course, that openings may, under proper conditions, be made through the bulkhead itself. Furthermore, 80 transverse bulkheads 22 may be provided along the ship, if desired.

The invention, however, has reference more particularly to the hull structure as a whole in relation to the stresses therein, and 85 the provision of a rigid structure wherein lateral stresses, developed by a tendency of the ship to "hog," are resisted by the transverse frame members of said structure, and also to prevent the yielding of the bow and 90 stem and of the working of the bilges by providing a continuous, laminated and reinforced bilge portion. To this end, and as hereinbefore set forth, the longitudinal bulkhead 17, which is in the nature of a beam, is 95 made an integral part of the structure through the stem and stern posts connections, and is, furthermore, held under an initial compression through the deck frames 13 and the upper member 14 and lower member 15 of the double bottom. The latter member is placed under an initial bending stress, to make the entire structure more rigid by providing longitudinal separator members or stringers 25 between said upper 100 member 14 and the lower member 15, the latter being made the heavier. The ends of said members are suitably bolted together through blocks or stays 26. The bottom trusses, thus produced, may be formed or 110 rather closed at certain intervals to provide transverse bulkheads along the bottom. The

exterior frame members, constituted by the bottom, sides and upper deck are thus all placed under a lateral stress; while the interior frame members, constituted by the 5 intermediate deck member and the longitudinal bulkhead, are placed under a corresponding compressive stress.

The bilges, as aforesaid, are curved and are preferably composed of laminations or 10 curved planking 30 of different lengths, the outer ones being made the longer. The ends of same are secured to the respective members 15 and 20 by means of bolts 31 extending transversely therethrough to prevent working of the bilge. The bilges are further reinforced by metal straps 32 and 15 33, the former being located between the outer of the laminated members and the inner wall of the outer skin, while the latter extends over the inner wall of the inner skin, the bolts 31 aforesaid extending 20 through both straps. Furthermore, the inner ends of the said straps extend respectively over the lower member 15 and upper 25 member 14 of the double bottom, and insure thereby, in conjunction with the laminations aforesaid, an extremely rigid and substantial union between the bilge and the bottom. In the case of the side frames 20, the 30 outer strap 32 is also continued beyond the laminations and secured to the frames through bolts 34.

I claim:

1. In a ship, a wooden hull, comprising: 35 transverse frame members, and means to retain same under an initial stress; a stem and a stern post; and a vertical, longitudinal bulkhead extending the entire length of the hull and forming an integral part of 40 said stem and stern posts, said bulkhead being continuous and insuring a rigid structure wherein lateral stresses, developed by a tendency of the ship to "hog," are resisted by the transverse frames acting in 45 conjunction with the said longitudinal bulkhead.

2. In a ship, a wooden hull, comprising: 50 transverse frame members, and deck frames retaining same under an initial stress; a stem and a stern post; and a vertical, longitudinal bulkhead extending the entire length of the hull and forming an integral part of said stem and stern posts, said bulkhead being continuous and insuring a rigid 55 structure wherein lateral stresses, developed by a tendency of the ship to "hog," are resisted by the transverse frames acting in conjunction with the said longitudinal bulkhead.

60 3. In a ship, a wooden hull, comprising: transverse frame members; a stem and a stern post; and a vertical, longitudinal bulkhead forming an integral part of said stem and stern posts, said bulkhead being continuous and under an initial compression, 65

and insuring a rigid structure wherein lateral stresses, developed by a tendency of the ship to "hog," are resisted by the transverse frames acting in conjunction with the said longitudinal bulkhead.

4. In a ship, a wooden hull, comprising: 70 transverse frame members, and means to retain same under an initial stress; a stem and a stern post; and a vertical, longitudinal bulkhead located between the bottom and 75 decks of the ship and maintained by same under an initial compression, and insuring a rigid structure wherein lateral stresses, developed by a tendency of the ship to "hog," are resisted by the transverse frames acting 80 in conjunction with the said longitudinal bulkhead.

5. In a ship, a wooden hull, comprising: 85 transverse frame members and means to retain same under an initial stress; a stem and a stern post; curved bilges under an initial stress; and a vertical, longitudinal bulkhead extending the entire length of the hull and forming an integral part of said stem and stern posts, said bulkhead being continuous and under an initial compression 90 and insuring a rigid structure wherein lateral stresses, developed by a tendency of the ship to "hog," are resisted by the transverse frames acting 95 in conjunction with the said longitudinal bulkhead.

6. In a ship, a wooden hull, comprising: 100 transverse frame members and intermediate and upper deck frames retaining the transverse frames under an initial stress; a stem and stern post; and a vertical, longitudinal bulkhead extending the entire length of the hull and forming an integral part of said stem and stern posts, said bulkhead being continuous and under an initial compression 105 and insuring a rigid structure wherein lateral stresses, developed by a tendency of the ship to "hog," are resisted by the transverse frames acting in conjunction with the said longitudinal bulkhead.

7. In a ship, a wooden hull, comprising: 110 transverse frame members and intermediate and upper deck frames retaining the transverse frames under an initial stress; a stem and a stern post; and a vertical, longitudinal bulkhead extending the entire length of the hull and forming an integral part of 115 said stem and stern posts, said bulkhead being maintained under an initial compression by the upper deck frame and bottom 120 of the ship and connected with the transverse frame members, thereby insuring a rigid structure wherein lateral stresses, developed by a tendency of the ship to "hog," 125 are resisted by the transverse frames acting in conjunction with the said longitudinal bulkhead.

8. In a ship, a wooden hull, comprising: 130 transverse frame members; a stem and a stern post; a double bottom, the upper por-

- tion being under a bending stress; and a vertical, longitudinal bulkhead extending the entire length of the hull and forming an integral part of said stem and stern posts, 5 said bulkhead being continuous and insuring a rigid structure wherein lateral stresses, developed by a tendency of the ship to "hog," are resisted by the transverse frames acting in conjunction with the said longitudinal bulkhead.
- 10 9. In a ship, a wooden hull, comprising: transverse frame members under an initial stress; curved bilges under an initial stress; a stem and a stern post; a double bottom, the lower member being the heavier, means included between the bottom members to produce a bending stress upon the upper member; and a vertical, longitudinal bulkhead forming an integral part of said stem and 15 stern posts, located between the bottom and decks of the ship and maintained by same under an initial compression, insuring a rigid structure wherein lateral stresses, developed by a tendency of the ship to "hog", 20 are resisted by the transverse frames acting in conjunction with the said longitudinal bulkhead.
- 25 10. In a ship, a wooden hull, comprising: transverse frame members; a stem and a stern post; a double bottom, the lower member being heavier; separator means between same, to hold the same under a bending stress; and a vertical, longitudinal bulkhead extending the entire length of the hull and 30 forming an integral part of said stem and stern posts, said bulkhead being continuous and insuring a rigid structure wherein lateral stresses, developed by a tendency of the ship to "hog", are resisted by the transverse 35 frames acting in conjunction with the said longitudinal bulkhead.
- 40 11. In a ship, a wooden hull, comprising: transverse frame members; a stem and a stern post; a double bottom, the lower members being the heavier; separator means between the same to hold the same under a bending stress, said separator means affording transverse bulkheads; and a vertical, longitudinal bulkhead extending the entire 45 length of the hull and forming an integral part of said stem and stern posts, said bulkhead being continuous and insuring a rigid structure wherein lateral stresses, developed by a tendency of the ship to "hog", are resisted by the transverse frames acting in conjunction with the said longitudinal bulkhead.
- 55 12. In a ship, a wooden hull, comprising: transverse frame members; a stem and a stern post; a curved bilge, comprising a plurality of curved planks, iron straps on the outside of said planks, and iron straps on the inside lining of the ship, bolts passing through said planks and straps; and a vertical, longitudinal bulkhead extending the entire 60 length of the hull and forming an integral part of said stem and stern posts, said bulkhead being continuous and insuring a rigid structure wherein lateral stresses, developed by a tendency of the ship to "hog", are resisted by the transverse frames acting in conjunction with the said longitudinal bulkhead.
- 65 13. In a ship, a wooden hull, comprising: transverse frame members; a stem and a stern post; a double bottom; a curved bilge, comprising a plurality of planks, iron straps on the outside of said planks, and iron straps on the inside lining of the ship, bolts passing through said planks and straps, the inner ends of said straps extending beyond the ends of the upper and lower members of the double bottom; and a vertical, longitudinal bulkhead extending the entire length of the hull and forming an integral part of 70 said stem and stern posts, said bulkhead being continuous and insuring a rigid structure wherein lateral stresses, developed by a tendency of the ship to "hog", are resisted by the transverse frames acting in conjunction with the said longitudinal bulkhead.
- 75 14. In a ship, a wooden hull, comprising: transverse frame members; a stem and a stern post; a bilge, comprising a plurality of curved planks, the radius of curvature 80 of said bilge being the same for the entire length thereof; and a vertical, longitudinal bulkhead extending the entire length of the hull and forming an integral part of said stem and stern posts, said bulkhead being continuous and insuring a rigid structure wherein lateral stresses, developed by a tendency of the ship to "hog", are resisted by the transverse frames acting in conjunction with the said longitudinal bulkhead.
- 85 15. In a ship, a wooden hull, comprising: transverse frame members; a stem and a stern post; a bilge, comprising a plurality of curved planks, the radius of curvature 90 of said bilge being the same for the entire length thereof; and a vertical, longitudinal bulkhead extending the entire length of the hull and forming an integral part of said stem and stern posts, said bulkhead being continuous and insuring a rigid structure wherein lateral stresses, developed by a tendency of the ship to "hog", are resisted by the transverse frames acting in conjunction with the said longitudinal bulkhead.
- 95 16. In a ship, a wooden hull comprising: transverse frame members; a stem and a stern post; a bilge, comprising a plurality of curved planks, the radius of curvature 100 of said bilge being the same for the entire length thereof, the curved plank members of the bilge being of different length, and the outer ones thereof being the longer; and a vertical, longitudinal bulkhead extending the entire length of the hull and forming an integral part of said stem and stern posts, said bulkhead being continuous and insuring a rigid structure wherein lateral stresses, developed by a tendency of the ship to "hog", are resisted by the transverse frames acting in conjunction with the said longitudinal bulkhead.
- 105 17. In a ship, a wooden hull comprising: transverse frame members; a stem and a stern post; a bilge, comprising a plurality of curved planks, the radius of curvature 110 of said bilge being the same for the entire length thereof, the curved plank members of the bilge being of different length, and the outer ones thereof being the longer; and a vertical, longitudinal bulkhead extending the entire length of the hull and forming an integral part of said stem and stern posts, said bulkhead being continuous and insuring a rigid structure wherein lateral stresses, developed by a tendency of the ship to "hog", are resisted by the transverse frames acting in conjunction with the said longitudinal bulkhead.
- 115 18. In a ship, a wooden hull comprising: transverse frame members under an initial stress; a stem and a stern post; a double bottom, the upper portion being under a bending stress; a laminated bilge secured to said transverse frame members and said double bottom and under an initial stress; and a vertical, longitudinal bulkhead ex- 120
- 130

tending the entire length of the hull, forming an integral part of said stem and stern posts and located between the bottom and decks of the ship, and maintained by same under an initial compression, insuring a rigid structure wherein lateral stresses, developed by a tendency of the ship to "hog", are resisted by the transverse frames acting in conjunction with the said longitudinal bulkhead.

10 17. In a wooden ship: a two-part bottom, the lower member thereof being the heavier, and separator means included between the floor members to produce a bending stress in the upper member.

15 18. In a wooden ship: a two-part bottom, the lower member thereof being the heavier, and separator means affording transverse bulkheads and included between the floor members to produce a bending stress in the upper member.

20 19. In a wooden ship: a curved bilge, comprising a plurality of curved planks, iron

straps on the outside of said planks, iron straps on the inside lining of the ship, and 25 bolts passing through said planks and straps.

20. In a wooden ship: a double bottom, a curved bilge, comprising a plurality of curved planks, iron straps on the outside of 30 said planks, iron straps on the inside lining of the ship, and bolts passing through said planks and straps, the inner ends of said straps extending beyond the ends of the upper and lower members of the double bottom.

35 21. The method of increasing the rigidity of a wooden ship, which consists in placing all of the exterior frame members under a lateral stress and the interior coacting members under a corresponding compressive 40 stress.

Signed at New York, in the county of New York and State of New York, this 1st day of December, A. D. 1917.

WILLIAM T. DONNELLY.
